THOMAS WALSH, JOHN WALSH, AND DAVID EVANS, OF BROWNSVILLE,
PENNSYLVANIA.

Letters Patent No. 64,726, dated May 14, 1867.

IMPROVED BRICK MACHINE.

The Schedule referred to in these Letters Patent and making part of the same.

TO ALL WHOM IT MAY CONCERN:

Be it known that we, THOMAS WALSH, JOHN WALSH, and DAVID EVANS, of Brownsville, in the county of Fayette, and State of Pennsylvania, have invented a new and improved Brick Machine; and we do hereby declare that the following is a full, clear, and exact description thereof, which will enable those skilled in the art to make and use the same, reference being had to the accompanying drawings, forming part of this specification, in which—

Figure 1, Sheet No. 1, is a side view of my invention.

Figure 2, a plan or top view of the same.

Figure 3, Sheet No. 2, a side sectional view of the same taken in the line $x\ x$, fig. 2.

Figure 4, an end view of the same; and

Figure 5, a transverse vertical section of the same taken in the line $y\ y$, fig. 3.

Similar letters of reference indicate corresponding parts.

This invention relates to a new and improved machine for pressing and moulding bricks, and it consists in a novel construction and arrangement of parts operating as hereinafter fully shown and described, whereby a very compact, strong, and durable machine for the purpose specified is obtained, and one which will perform the work expeditiously with but a moderate application of power.

A represents a horizontal bed or platform, supported at a suitable height by legs a , and having upon it an upright framing, B, in which a horizontal driving-shaft, C, is placed, having a crank, D, at one end, and a pinion, E, upon it near the crank. On said shaft C, at about the centre of the width of the framing B, there is keyed a cam, F, which works within a yoke, G; a vertical guide-rod, H, being at the top of the yoke, and which works through a cross-bar, b, at the upper part of the framing B. To the lower end of the yoke a plunger, I, is attached, which works in a box or chamber, J, in the lower part of the framing B. At two opposite sides of this box or chamber J there are attached hoppers K K, in which horizontal rotating shafts L L are placed, said shafts having radial pins c attached. The lower parts of these hoppers communicate with the box or chamber J by means of openings d, which are just below the shafts L L, and in each of these openings a slide, M, works, one slide only being shown. The outer ends of these slides are slotted longitudinally, as shown at e, and in said slots the upper ends of rods f are fitted, the latter being attached to a slide, N, fitted in the bed or platform A, and working over an opening, g, therein. This slide N has two sets of these openings h in it, one set at its centre and the other set near one end, and an opening, i, is also made in the slide, the use of which will presently be shown. The slide N has a reciprocating motion imparted to it by means of a cam, O, working in a yoke, P, attached to the slide, the cam being on a shaft, Q, which has a wheel, R, upon it, the latter gearing into a wheel, S, which gears into the pinion E on shaft C. The upper end of the plunger I has arms j projecting obliquely from it, each arm having a pendent bar, K, attached to the lower ends of which plunger-bars T are secured, each plunger-bar having three plungers, l, attached, to work into the openings h, which serve as moulds. The chamber J, in which the plunger I works, has two vertical grooves, n n, in it, and the chamber J is provided with two vertical partitions, o o, as shown clearly in fig. 5, and when the plunger I descends the grooves n n receive the partitions o o, and admit of the plunger passing down to the bottom of the chamber. The compartments p, formed by the partitions o o, correspond to the openings h in the slide N, so that at the termination of each movement of the slide, one of the sets of openings h will be at the bottom of and in line with the compartments p. The rotary shafts L are driven by belts q from the shaft C.

The operation is as follows: The power is applied to the shaft C, and the clay, properly moistened, is thrown into the hoppers K K, and tempered by the action of the pins c of the shafts L. The slides M force the requisite quantity of clay into the chamber J, each compartment p receiving a quantity requisite to fill an opening h, in the slide N, and when the plunger I descends this clay is forced into the openings h at the bottom of the compartments p, and the clay is compressed therein. As the plunger I rises the slide N is moved by the cam O so as to draw the filled openings or moulds h out from underneath the chamber J, and in line with the plungers l at one side of the chamber J. When the plunger I again descends, the plungers l over the filled moulds or

openings *h* also descend, and force the clay out of the moulds, while the plunger *I* is pressing the clay into the other set of moulds or openings *h*, which are at the bottom of the compartments *p* in *J*. The slides *M* are moved so as to force the clay into the chamber *J* just previous to each descent of the plunger *I*, so as to insure the moulds being filled with clay at each descent of plunger *I*. The opening *i* in the slide *N* is to receive the plungers *l* at the side of the chamber *J* towards the yoke *P* when the moulds *h*, out of which said plungers *l* force the clay, are under the compartments *p* of *J*, and are having the clay pressed into them by plunger *I*. The plungers *I* & *l*, it will be seen, are operated by the cam *F*. The machine is very compact, and performs its work very expeditiously and in a perfect manner.

Having thus described our invention, we claim as new, and desire to secure by Letters Patent—

1. The slotted or grooved plunger *I*, working in the chamber *J*, provided with the partitions *o*, in combination with the plungers *l* and the slide *N*, provided with the moulds *h*, all arranged to operate substantially in the manner as and for the purpose set forth.

2. The slides *M*, working through the hoppers *K* *K* and in openings *d* in the sides of the chamber *J*, in combination with the rotary shafts *L*, provided with the pins *c*, substantially as and for the purpose specified.

3. The combination and arrangement of the reciprocating slide *N* provided with the openings or moulds *h*, the plungers *I* & *l*, chamber *J*, slides *M*, and hoppers *K* *K*, provided with the rotary shafts *L*, having pins *c* attached, all arranged substantially as and for the purpose set forth.
